COMBINED TABLE AND DRAWING EASEL

Leslie L. Westeamp, Fair Oaks, Calif.

Application January 29, 1949, Serial No. 73,596

4. Claims. (Cl. 311—38)

1

This invention is directed to, and it is an object to provide, a novel piece of children's furniture in the form of a combined table and drawing easel.

Another object of the invention is to provide a combined table and drawing easel which includes an upstanding supporting frame and a flat panel adjustable between a horizontal position on the support for use as a table, and an inclined position for use as a drawing easel.

A further object of the invention is to provide a combined table and drawing easel, as above, which includes a novel mount adapted to secure the flat panel to the support for selective adjustment between said positions. Additionally, this mount permits of easy removal of the panel from the support if desired.

An additional object of the invention is to provide a combined table and drawing easel which is especially designed and adapted for use in the home and schools by children; the structure being simple but rugged, and thus not subject to ready damage.

A still further object of the invention is to provide a combined table and drawing easel which is steady in either position of use.

Still another object of the invention is to provide a practical and reliable combined table and drawing easel, and one which is exceedingly effective for the purpose for which it is designed.

These objects are accomplished by means of such structure and relative arrangement of parts as will fully appear by a perusal of the following specification and claims.

In the drawings:

Fig. 1 is an end elevation, partly broken away, of the combined table and drawing easel adjusted for use as a table.

Fig. 2 is a similar view, but shows the device adjusted for use as a drawing easel.

Fig. 3 is a bottom plan view of the panel, detached.

Fig. 4 is an end elevation similar to Fig. 1, but illustrates a modified adjustable mount for the panel.

Referring now more particularly to the characters of reference on the drawings, and particularly at present to Figs. 1-3, inclusive, the combined table and drawing easel for children comprises an upstanding support, indicated generally at 1, which is of tubular metal construction.

The upstanding support 1 comprises four corner legs 2, with said legs at corresponding ends of the support connected by an integral floor bar 3.

2

Transverse top bars 4 and 5 connect corresponding legs 2 at the front and rear, respectively, of the support 1 at the upper ends of said legs. A stay bar 6 extends between the top bars 4 and 5 intermediate their ends; said stay bar 6 being offset downwardly with respect to the bars 4 and 5 by reason of upturned end portions 7 on said stay bar.

A rigid, rectangular panel 8, preferably of "Masonite" or the like, is disposed above the support 1, being adjustably mounted in connection therewith for use in a horizontal position as a table (see Fig. 1), or for use in an inclined position as a drawing easel (see Fig. 2). The adjustable mount for the panel 8 comprises the following:

On the under side thereof the panel 8 is fitted with a pair of cross cleats 9 and 10 disposed in parallel relation and spaced apart a predetermined distance; such cross cleats being symmetrical on said panel.

The cross cleat 9 is formed along the outer side thereof with a longitudinal, outwardly opening cradle or groove 11; such groove receiving the transverse top bar 4 when the panel 8 is disposed on the support 1 with the cross cleats 9 and 10 engaging the top bars 4 and 5 from the inner side thereof.

The outer and lower longitudinal edges of the cross cleats 9 and 10 are beveled, as at 12 and 13; such bevel portions being fitted, intermediate their ends, each with a turn-catch 14 and 15, respectively. These turn-catches 14 and 15, when turned to a transverse position with respect to the corresponding cross cleats 9 and 10, serve to lock the latter against escape from the top bars 4 and 5. In this manner the panel 8 is effectively maintained on the support 1 in a horizontal position, and for use as a table.

To adjust the panel 8 to an inclined position, as in Fig. 2, for use as a drawing easel, the turn-catch 15 is released and the panel 8 then swung upwardly about the transverse top bar 4 as an axis; the cross cleat 9 and turn-catch 14 then serving in the nature of a hinge assembly. The panel 8 is maintained in its inclined position, for use as a drawing easel, by means of a supporting leg 16 which extends from the then elevated cross cleat 10 downwardly to detachable connection with the transverse top bar 5.

The supporting leg 16 is Y-shaped, with its open end straddling and pivoted to the ends of the cross cleat 10, as at 17. At its opposite end the supporting leg is formed with a spring hook 18 which frictionally but releasably engages over

the transverse top bar 5, as clearly shown in Fig. 2.

When the panel 1 is in use in its horizontal position as a table, the supporting leg 16 is folded up against the under side of said panel in the manner shown in Figs. 1 and 3.

In the embodiment of Fig. 4 the general assembly remains the same, and includes an upstanding support, indicated generally at 19, and a panel 20 adapted for horizontal use as a table, 10 or inclined as a drawing easel.

Here, however, the mount comprises cross cleats 21 and 22, both of which are longitudinally grooved, as at 23 and 24, on corresponding sides; i. e. with the grooves facing in the same direction. The longitudinally grooved cross cleat 21 engages one top bar 25 from the inner side, being normally secured to said bar by a turn-catch 26. The longitudinally grooved cross cleat 22 engages and receives the other top bar 27 from the outer side. In this manner the panel 20 is held in its horizontal position for use as a table.

To adjust the panel 20 to its inclined position for use as a drawing easel, the turn-catch 26 is rotated to its unlatching position, releasing cleats 21 and 22 from positive engagement with the top bars 25 and 27. The edge of the panel 20 adjacent cleat 22 is then raised until cleat 22 is disengaged from the top bar 27. The cross cleat 21 is then engaged with the top bar 25 and secured by turn-catch 26, and the panel 20 is swung to said inclined position, being then maintained in such position by a supporting leg 28 which corresponds to the leg 16 in the embodiment of Fig. 1.

The described combined table and drawing easel, in either of its embodiments, provides a very practical and convenient piece of furniture for use by children; the adjustment of the panel between its respective positions of use being accomplished readily and easily.

The device is relatively light-weight and thus capable of easy manual transport from place to place, and the construction is such as to minimize wear or tear or damage.

While designed primarily for home or school use, the device may obviously be put to many other uses.

In either embodiment of the device the top panel can be easily removed from the support for the purpose of manual transport, or compact storage; regardless of the panel being accomplished merely by rotating the turn-catches to free positions and then lifting upwardly on the panel.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A combined table and drawing easel comprising an upstanding support having spaced, parallel top bars, a flat, rigid panel above the support, cross cleats secured on the under side of the panel in position to engage lengthwise alongside corresponding top bars, and turn-

5 catches on the cross cleats in position to intersect the corresponding top bars in holding relation thereto; one cross cleat and the corresponding turn-catch providing a hinge assembly for swinging of the panel, about one top bar, to an inclined position from a horizontal position upon release of the turn-catch on the other cross cleat from the other top bar, and a pivoted leg secured to the under side of the panel in position to then 10 extend to and releasably connect with said other top bar.

2. A combined table and drawing easel comprising an upstanding support having spaced, parallel top bars, a flat, rigid panel above the support, cross cleats secured on the under side of the panel in position to engage lengthwise alongside corresponding top bars, one cross cleat having a longitudinal groove in the outer side and the adjacent top bar engaging in said groove, 15 a turn-catch mounted on said one cross cleat in position to releasably intersect said adjacent top bar and to retain the same in the groove, another turn-catch mounted on the other cross cleat in position to releasably intersect the other top bar in holding relation, and a supporting leg pivoted on the under side of the panel, in position to extend from the panel to connection with said other top bar when said other turn-catch is released and the panel swung upward to an inclined position.

3. A combined table and drawing easel comprising an upstanding support having spaced, parallel top bars, a flat, rigid panel above the support, cross cleats secured on the under side of the panel in position to engage lengthwise alongside corresponding top bars, one cross cleat having a longitudinal groove in the outer side and the adjacent top bar engaging in said groove, 20 a turn-catch mounted on said one cross cleat in position to releasably intersect said adjacent top bar and to retain the same in the groove, another turn-catch mounted on the other cross cleat in position to releasably intersect the other top bar in holding relation, and a supporting leg pivoted on the under side of the panel in position to extend from the panel to connection with said other top bar when said other turn-catch is released and the panel swung upward to an inclined position.

4. A combined table and drawing easel comprising an upstanding support having spaced, parallel top bars, a flat, rigid panel above the support, cross cleats secured on the under side of the panel in position to engage lengthwise along the inner side of corresponding top bars, a 25 longitudinal groove in the outer side of one cross cleat, the corresponding top bar seating in the groove, the lower outer corners of the cross cleats being beveled, and turn-catches on said beveled portions of the cross cleats releasably intersecting the corresponding top bars in holding relation; there being a supporting leg pivoted on the under side of the panel in position to extend to connection with the cross bar corresponding to the other cross cleat when the latter is released and the easel is swung upward to an inclined position.
